PRESSURE CASTING DIE

Nathan Lester, Cleveland Heights, and Adrian E. Weiss, University City, Ohio, assignors, by mesne assignments, of one-half to Lester Engineering Company, Cleveland, Ohio, a corporation of Ohio, and one-half to The Superior Die Casting Company, Cleveland, Ohio, a corporation of Ohio

Application February 1, 1936, Serial No. 61,844

9 Claims. (Cl. 22—93)

The present invention relates to an improved form of permanent mold or die construction adapted to be used in a pressure casting machine wherein molten metal is forced under pressure into the die cavity. More particularly the invention pertains to a novel construction for the core assembly of a pressure casting die in which hollow articles such as an internal combustion engine piston, are cast.

The general object and nature of the invention is to provide a core assembly for such a casting die which is capable of automatic and high production operation. A further object of the invention is to co-relate the movement of the core pieces making up the core assembly with the opening and closing movement of the pressure casting dies. Still another object is to provide a novel form of slidable interlock between the individual pieces of the core assembly. Additional objects and advantages shall become apparent as the following description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a view taken upon the face of one of the die blocks showing the core assembly embodying the principle of our invention in position thereon; Fig. 2 is a view taken upon a plane normal to that of Fig. 1, being sectioned substantially along line 2—2 of said figure and showing the two die blocks in closed position; Fig. 3 is a sectional view taken along line 3—3 of Fig. 1; and Fig. 4 is a sectional view taken along line 4—4 of Fig. 1; Fig. 5 is a view taken upon the face of one of the die blocks showing an alternative form of core assembly wherein the parting faces of the core pieces are parallel to the parting face of the die blocks, as distinguished from the assembly shown in Figs. 1 to 4 inclusive where the parting faces of the core pieces are at right angles to the die block parting faces; Fig. 6 is a view taken normal to that of Fig. 5 and being sectioned substantially along line 6—6 of said figure and showing the die blocks and core assembly in closed position; Fig. 7 is a view similar to Fig. 6 but showing the die blocks and core assembly in open position; Fig. 8 is a sectional view

taken substantially along line 8—8 of Fig. 5; Fig. 9 is a sectional view taken substantially along line 9—9 of Fig. 5; Fig. 10 is an enlarged detailed view of the assembled core pieces of the form of construction shown in Figs. 5 to 7; Fig. 11 is a sectional view taken upon a plane normal to that of Fig. 10; Fig. 12 is a sectional view taken substantially along line 12—12 of Fig. 10.

Now referring more particularly to the drawings, there are shown therein a die block 1 and a die block 2 whose opposed faces meet along the parting line 3. The die blocks 1 and 2 are adapted of course to be mounted upon die plates (not shown) of a pressure casting machine such as is disclosed in our joint copending application Ser. No. 29,638, filed July 8, 1935. A pressure casting chamber or cylinder 4 and a measuring plunger cylinder 5 are located in the die blocks 1 and 2 respectively. A sprue opening 6 leads from the cylinders 4 and 5, along the parting line 3, to the die cavity 7. The outer walls of the die cavity 7 are formed by the die halves 8 and 9 which are removably secured to the respective die blocks 1 and 2 by suitable fasteners 10, whereby such outer wall die halves 8 and 9 may be replaced, or changed for the purpose of accommodating different sizes or patterns of castings.

In the present instance, the die cavity 7 is shown as being in the form for producing an internal combustion engine piston which conventionally consists of a head portion, a skirt portion, and internally extending wrist pin bosses 11 and 12. As best shown in Figs. 1 and 4, the core pins 13 and 14 extend through the walls of the die cavity 7 and as far as the ends of the bosses 11 and 12 respectively. The core pins 13 and 14 are respectively mounted upon slidable guide blocks 15 and 16 which are in turn carried by the die block 2 and slidably locked thereto by T-slots 17 and 18 respectively. Angularly inclined horns or pins 20 and 21 are mounted in the die block 1 and extend through complementary holes 20' and 21' in the guide blocks 15 and 16. Thus, when the die blocks 1 and 2 are moved into open position, the guide blocks 15 and 16 being carried by the die block 2, will travel outwardly with respect thereto and thereby draw the core pins 13 and 14 in the same direction and out of their position in the interior of the die cavity 7. It will be noted that the openings in the die block 2 in which the pins 20 and 21 are received, are enlarged as at 19 (Fig. 4) so that there is clearance for the outer ends of the pins 20 and 21 as the die blocks are opened and closed.

The inner walls of the die cavity 7 are formed

by a core assembly consisting of a centrally disposed core piece 22 and outer core pieces 23 and 24 on both sides thereof. The meeting faces of the core pieces 22, 23 and 24 are slidably interlocked by means of a dove tail joint 25. That portion as indicated at 25' of the meeting faces of the core pieces which extends from the inner wall of the die cavity 1 (the outer wall of the core pieces 22, 23 and 24) to the dove tail joint 25 is 10 in a radial direction with respect to the axial center of the casting. In this manner the parting line of the core pieces 22, 23 and 24 adjacent the die cavity 1 is normal thereto and the pressure exerted upon the core assembly of the casting die 15 will tend to force the core pieces tightly together along the parting line so that the casting metal will not have an opportunity to be forced there-between.

Those portions of the core pieces 22, 23 and 24 20 which do not form the core assembly proper extend outwardly beyond the die cavity 1 as indicated at 22', 23' and 24' respectively. The portion 22' of the central core piece 22 is connected to a draw bar 26 by means of the dowel pins 27. An 25 inclined shoulder 28 is formed on the draw bar 26 and adapted to bear against a hardened metal insert 29 in the face of the die block 1. When the surface of the insert 29 bears against the inclined shoulder 28 as the die blocks 1 and 2 are 30 moved into closed position, the draw bar 26 together with the central core piece 22 is thus forced and held in a securely locked position. The outer end of the draw bar 26 is slidably carried in a guide block 30. A gear rack 31 on one 35 face of the draw bar 26 is engaged by the gear teeth 32 on the shaft 33 journaled in the guide block 30. Gears 34 on each end of the shaft 33 engage with idler gears 35 mounted upon the stub shafts 36. The idler gears 35 in turn engage 40 with the gear racks 37 on the bars 38 carried by the die block 1. The guide block 30 is carried by the die block 2 and secured thereto in suitable fashion such as by the plate 40 with fasteners 41 and 42 and the angular arm 43 with fasteners 44 and 45. Thus it will be seen that the gear rack bar 38 moves with the die block 1 and the guide block 30 moves with the die block 2. As the die blocks 1 and 2 are moved with respect to each other, the gear racks 37 will rotate the idler gears 45, gears 34, shaft 33, gear 32 and gear rack 31 with the result that the draw bar 26 will be moved inwardly and outwardly as the case may be with respect to the die cavity 1.

The outer portion 23' of the core piece 23 is 55 mounted upon a movable base plate 50 by means of suitable fasteners in the drilled holes 45 and 46. The outer portion 24' of the core piece 24 is carried by a guide block 47 and secured thereto by suitable fasteners located in the drilled holes 60 48 and 49. The guide block 47 is slidably mounted in the movable base plate 50 and locked thereto by means of a T slot as indicated at 51 and 52. An angularly inclined horn or pin 54 is mounted in the die block 2 and received in a complementary hole 55 in the guide block 47. As is shown in Fig. 3, the hole 55 also extends into the die block 1 for possible clearance of the end of the pin 54. The movable base plate 50 is carried by guide pins 56 which are mounted in the die block 2. Ejector 65 pins 58 connect the movable base plate 50 to the ejector mechanism, part of which is indicated at 70 59. Thus, when the die blocks 1 and 2 are moved into open position and the ejector pins 58 are actuated to move in an upward direction with 75 respect to Fig. 2, the movable base plate 50 will

be moved away from the face of the die block 2 and the pin 54 will cooperate with the hole 55 in the block 47 to move the latter, together with the core piece 24 in an upward direction with respect to Fig. 3 and toward the center of the casting. The movable base plate 50 has a portion removed as indicated at 60, adjacent the pin 54 in order to provide the necessary clearance.

The structure of the apparatus embodying our invention having been described and the operation of its component parts partially set forth, the complete cycle of operations will now be explained:

When the die blocks 1 and 2 are in closed position as indicated in Fig. 2 and the core pieces 22, 23 and 24 are in position in the interior of the die cavity 1, a charge of molten metal is introduced through the casting cylinder 4, thence through the sprue opening 6 to the die cavity 1. After such casting operation, the die blocks 1 and 2 are moved away from each other and the central core piece 22 is thereby drawn in a right hand direction with respect to Figs. 1 and 2, and out from between the core pieces 23 and 24 leaving a vacant space. Simultaneously, upon moving apart of the die blocks 1 and 2, the wrist pin and core pieces 13 and 14 are also withdrawn from within the die cavity 1 as previously described. After the core pieces 13, 14 and 22 have been withdrawn, the ejector pins 58 are actuated to move the movable base plate 50 away from the die block 2 and simultaneously the core piece 24 is moved into the space vacated by the central core piece 22. The resultant casting thereby is in contact with and supported by only the core piece 23 from which it may be conveniently lifted by the operator. The above described cycle of operations is then reversed and the parts returned to their initial position ready for another pressure casting charge.

In the modified form of construction illustrated in Figs. 5 to 12 inclusive, the core pieces have been rotated through an angle of 90° with respect to the position which they occupy in the form of construction just described in connection with Figs. 1 to 4. That is to say, the parting faces of the core pieces are disposed in planes parallel to the parting faces of the die blocks.

The die blocks 1' and 2' and the die cavity 1', as shown in Figs. 5 and 6 are similar to those previously described, with the pressure casting cylinder 4' and the sprue opening 6' leading into the die cavity. A core pin 65 is mounted in the die block 1' and has a gear rack engaging with the pinion 66. A manually operated crank for power operating means such as a hydraulic cylinder may be connected to the pinion 66 in the customary manner and by this means the core pin 65 can be moved inwardly and outwardly of the die cavity 1'. A second core pin 67 extends through the die block 2' and is permanently mounted upon the ejector box 68.

The central core piece 69 together with the two outer core pieces 70 and 71 constitute the core assembly for the piston casting. The central core piece 70 is connected to a slide or guide member 72 which is carried in the guide housing 73. The guide housing 73 is in turn supported by the fixed brackets 74 and 75, the latter being attached to the base or frame (not shown) of the pressure casting machine. A pair of gear racks 76, 76 engage with the gear toothed shaft 77, which in turn also engages with the gear rack 78 on the guide member 72. The gear rack bars 76, 76 are

suitably operated by means of a hydraulic cylinder (not shown).

The guide member 72 carries an upwardly projecting block 78 which is adapted to move back and forth in the recess 80 in a second slide or guide member 81. The guide member 81 is connected to the outer core piece 70 by means of the lap joint as indicated at 83 and the dowel pins 84. The guide member 81 is also carried by the guide housing 73. The block 78 is adapted to abut against a shoulder 82 at the end of the recess 80 in the guide member 81.

The outer core piece 71 is connected to and carried by the block 85 which in turn is mounted upon the ends of the pins 86. The pins 86, 86 have the enlarged collar portions 87, 87 which bear against the face of the block or base plate 88. The ends of the pins 86, 86 extend into the ejector box as indicated at 88'.

The base plate 88 is engaged by the roller carrying pins 89 on the end of the levers 90. The rollers on the end of the pins 89 are adapted to work in elongated slots 91 in the side of the block 88. The levers 90 are mounted upon a fixed shaft 92 carried by the guide housing 73. The outer ends or the right hand ends (with respect to Figs. 5 and 6) of the levers 90 have laterally extending pins 93 carrying the rollers 94 which in turn are adapted to operate in the cam track 95 in the side of the guide member 72.

A draw bar 96 carrying the gear rack 97 is slidably mounted in the block 88. A cover plate 98 extends over the top of the bar 96 and carries the sleeve 99 surrounding the core pin 67. The right hand end of the bar 96 carries a transversely extending pin 100 with the rollers 100' adapted to travel in the slots 101 in the brackets 102 mounted upon the plate 103. The plate 103 is in turn carried by the ejector pins 104 and slidably engages with the guide pins 105.

The gear rack 97 on the bar 96 engages with a gear toothed shaft 106 mounted in the base plate 88. The shaft 106 also engages with gear racks 107 on the pins 86. The left hand end of the bar 96 is bifurcated or cut away as indicated at 108 in order to provide clearance for the core pin 67.

A coil compression spring 109 is mounted between the base plate 88 and the ejector block 68 and tends to force the block 88 towards the die block 2'.

A lock pin 110 is carried by the die block 1' and fits through apertures in the core pieces 69, 70 and 71 for the purpose of securely locking the core assembly together during the metal casting operation.

The operation of the last described apparatus is as follows: After the metal charge has been introduced to the die cavity 1' and through the sprue opening 6', the core pin 65 is withdrawn by operation of the pinion 66. The die blocks 1' and 2' are then moved to open position as shown in Fig. 7. Next, the rack bars 16 are operated to draw the central core piece 69 and guide member 72 outwardly. The rollers 94 travelling in the cam track 95 move in a downward direction with respect to Figs. 6 and 7, and operate to rotate the levers 90 about their fixed pivot 92 and to raise the left hand end of the levers 90 together with the base plate 88. As the base plate 88 thus goes in an upward direction into the position indicated in Fig. 7, the core pin 67 is stripped by means of the sleeve 99 and the pins 86 carry the outer core piece upwardly and into the space vacated by the central core piece

69. The spring 109 holds the base plate 88 and its attached parts in this position. The guide member 72 continues to travel in a right hand outward direction until the block 78 abuts against the shoulder 82 and also draws the slide or guide member 81, together with the outer core piece 70 into the withdrawn position as shown in Fig. 7.

The ejector pins 104 are then operated to carry the plate 103 away from or in an upward direction with respect to the ejector box 68. During such movement of the plate 103, the rollers 100' in the end of the draw bar 96 travel in a right hand direction in the slots 101 and thereby draw the bar 96 to the position shown in Fig. 7. During such right hand movement of the draw bar 96, the gear rack 97 rotates the toothed shaft 106 which in turn moves the pins 86 in an upward direction until the outer core piece 71, which now carries the casting, is in the position shown in Fig. 7. At this position, the casting is lifted off the core piece 71, the cycle of operations reversed and the parts assume their original position ready to repeat the casting operation.

The form of construction of the interlock between the core pieces 69, 70 and 71 is illustrated in detail in Figs. 10, 11 and 12. The purpose of the construction illustrated therein is to effect a slight drawing together or inward movement of the outer core pieces 70 and 71 upon the withdrawal of the central core piece 69. The central core piece 69 is longitudinally tapered from its free end to its fixed end, as illustrated in Fig. 11, with the result that the meeting faces 111 of the core pieces are slightly inclined. A dove tailed joint, as indicated at 112 slidably locks the outer core pieces 70 and 71 to the central core piece 69, and as the central core piece 69 is withdrawn from its position between the two outer core pieces, the latter are moved inwardly or drawn together a distance equal to the extent of the longitudinal taper of the central core piece 69. In actual practice this distance is preferably about one ten thousandth of an inch. Thus the core pieces are forcibly moved away from the inner walls of the casting a slight distance sufficient to prevent any "sticking", as the central core piece is withdrawn.

Although the above described embodiments of our invention disclose but one die cavity, or a "single impression" die, as it is known in practice, it should be obvious to those persons skilled in the art that more than one die cavity, such as a "double impression" die, could be used without transcending the scope of the invention. Such a change would merely require the addition of duplicate elements in the die block and core assembly.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected

to said guide member and adapted to move said guide member outwardly from said die upon separation of said die blocks, a base plate connected to said ejector mechanism and movable with respect to one of said die blocks, one of said outer core pieces being connected to said base plate, means for moving said last-named core piece with respect to said base plate, and means for moving said base plate with respect to said last-named die block.

10. 2. In a casting die, the combination of separable die blocks, an ejector mechanism movable with respect to said die blocks, a core member comprising a central core piece and a pair of outer core pieces adapted to make an interlocking fit with said central piece, a guide member carrying said central core piece, supporting means for said guide member connected to one of said die blocks, mechanism connecting said guide member to said die blocks and adapted to move said guide member outwardly with respect to said die upon separation of said die blocks, a guide plate carrying one of said outer core pieces, a base plate connected to said ejector mechanism and movable with respect to one of said die blocks and having said guide plate slidably mounted thereon, means for moving said guide plate with respect to said base plate, and means for moving said base plate away from one of said die blocks.

15. 3. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks mechanism connecting 20 said guide member to said die blocks and adapted to move said guide member outwardly from said die upon separation of said die blocks, a base plate connected to said ejector mechanism and movable with respect to one of said die blocks, 25 a guide plate movably mounted on said base plate, one of said outer core pieces being carried by said guide plate, an angularly inclined member extending outwardly from one of said die blocks, said guide plate having an inclined surface engaging with said inclined member, and means for moving said base plate away from said last-named die block whereby said inclined member cooperating with said inclined surface is adapted to move said guide plate with respect 30 to said base plate.

4. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connecting 45 said guide member to said die blocks and adapted to move said guide member outwardly from said die upon separation of said die blocks, a base plate connected to said ejector mechanism and movable with respect to one of said die blocks, one of said outer core pieces being carried by said guide plate, an angularly inclined pin extending outwardly from one of said die blocks, said guide plate having an inclined hole adapted to receive said inclined pin, and means for moving said base plate away from said last- 50

named die block whereby said inclined pin, co-acting with said inclined hole is adapted to move said guide plate with respect to said base plate.

5. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected to said guide member and adapted to move said guide member outwardly from said die upon separation of said die blocks, a base plate connected to said ejector mechanism and movable with respect to one of said die blocks, one of said outer core pieces being connected to said base plate, and means connected to said guide member for moving said base plate.

10. 6. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected to said guide member and adapted to move said 15 guide member outwardly from said die upon separation of said die blocks, a base plate connected to said ejector mechanism and movable with respect to one of said die blocks, one of said outer core pieces being connected to said base plate, and means connected to said guide member for moving said base plate, and means for moving said last-named core piece with respect to said base plate.

20. 7. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected to said guide member and adapted to move said 25 guide member outwardly from said die upon separation of said die blocks, a base plate connected to said ejector mechanism and movable with respect to one of said die blocks, one of said outer core pieces being connected to said base plate, means connected to said guide member for moving said base plate, and means for moving said last-named core piece with respect to said base plate.

30. 8. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected to said guide member and adapted to move said 35 guide member outwardly from said die upon separation of said die blocks, a base plate connected to said ejector mechanism and movable with respect to one of said die blocks, one of said outer core pieces being connected to said base plate, means connected to said guide member for moving said base plate, whereby said last-named core piece together with the casting is moved away from one of said die blocks, and means for moving said other outer core piece outwardly from said die.

40. 9. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected to said guide member and adapted to move said 45 guide member outwardly from said die upon separation of said die blocks, a base plate connected to said ejector mechanism and movable with respect to one of said die blocks, one of said outer core pieces being connected to said base plate, means connected to said guide member for moving said base plate, whereby said last-named core piece together with the casting is moved away from one of said die blocks, and means for moving said other outer core piece outwardly from said die.

means connected to said guide member for moving said base plate, whereby said last-named core piece together with the casting is moved away from one of said die blocks, and a second guide member located parallel to and engaging with said first-named guide member for moving said other outer core piece outwardly from said die.

9. In a casting die, the combination of separable die blocks, an ejector mechanism movable with respect to said die blocks, a core member for said die comprising a central core piece and a pair of outer core pieces adapted to make an interlocking fit with said central piece, a guide member carrying said central core piece, supporting means for said guide member connected to one of said die blocks, mechanism connected

to said guide member and adapted to move said guide member outwardly from said die upon separation of said die blocks, a base plate connected to said ejector mechanism and movable with respect to one of said die blocks, one of said outer core pieces being connected to said base plate, means connected to said guide member for moving said base plate, whereby said last-named core piece together with the casting is moved away from one of said die blocks, means for moving said other outer core piece outwardly from said die, and means for moving the first outer core piece and casting with respect to said base plate. 5
